[57] CLAIM

The ornamental design for a cabinet, as shown and described.

DESCRIPTION

FIG. 1 is a front perspective view of a cabinet, showing my new design;

FIG. 2 is a reduced top, rear, and left side perspective view thereof;

FIG. 3 is a right side elevational view thereof; and

FIG. 4 is an enlarged fragmentary perspective view thereof, showing the front handle in greater detail.

FIG. 1

FIG. 2

FIG. 3

FIG. 4
